UNITED STATES PATENT OFFICE.

FREDRIC M. PARKER, OF WORCESTER, MASSACHUSETTS, ASSIGNOR TO
WILLIAM JAMES HOGG, OF SAME PLACE.

DESIGN FOR CARPET.

SPECIFICATION forming part of Design No. 25,630, dated June 9, 1896.

Application filed May 1, 1896. Serial No. 589,911. Term of patent 3½ years.

To all whom it may concern:

Be it known that I, FREDRIC M. PARKER, a citizen of the United States, residing at Worcester, in the county of Worcester and 5 State of Massachusetts, have invented and produced a new and original Design for Carpets, of which the following is a specification.

My invention relates to a design to be worked into or upon carpeting or similar fabrics; and I do hereby declare that the drawing accompanying this specification gives and conveys to any one skilled in the art of carpet-weaving a clear understanding of the same that is sufficient to enable such persons to 15 use my invention.

The said drawing is a face view of a carpet embodying my new design. The drawing illustrates a body and a border.

The body A consists of a substantially uniform groundwork upon which appear disconnected floral figures or conventionalized chrysanthemums. These floral figures are arranged in an apparently careless manner, each having a short stem with a few leaves 25 attached.

The border B consists of a groundwork of

the same character as the body A. Upon this appear floral figures similar to those in the body, but arranged as if growing from a flowing leafy stem or vine. The inner edge 30 is defined by a series of small ornamental figures in a dotted effect. The outer edge is ornamented by a series of larger figures also in a dotted effect—figures of a general circular shape alternating with long narrow figures. 35 The extreme outer edge is left perfectly plain.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

FREDRIC M. PARKER.
